CLAIM

The ornamental design for a watch as shown and described.

DESCRIPTION

FIG. 1 is a top view of a watch of my present design;

FIG. 2 is a bottom view thereof;

FIG. 3 is a right side view thereof;

FIG. 4 is a left side view thereof;

FIG. 5 is a bottom view thereof;

FIG. 6 is a top view thereof; and

FIG. 7 is a top right perspective view thereof;

FIG. 8 is a bottom left perspective view thereof;

FIG. 9 is an enlarged portion of the watch as identified in FIG. 1;

FIG. 10 is another enlarged portion of the watch as identified in FIG. 1;

FIG. 11 is an enlarged portion of the watch as identified in FIG. 2;

FIG. 12 is an enlarged portion of the watch as identified in FIG. 7;

FIG. 13 is another enlarged portion of the watch as identified in FIG. 7; and,

FIG. 14 is an enlarged portion of the watch as identified in FIG. 8.

The broken lines depict portions of the watch that form no part of the claimed design.

The dot-dash broken lines represent the designation of enlargement views and form no part of the claimed design.
